DESIGN FOR A LAMP SHADE

Dan Denenberg, Philadelphia, Pa.

Application November 13, 1943, Serial No. 111,684

Term of patent 3½ years

(Cl. D48—16)

To all whom it may concern:

Be it known that I, Dan Denenberg, a citizen of the United States, residing at Philadelphia, in the county of Philadelphia and State of Pennsylvania, have invented a certain new, original, and ornamental Design for Lamp Shade, of which the following is a specification, reference being had to the accompanying drawing, forming part thereof.

In the drawing:

Fig. 1 is a side elevational view of a lamp shade embodying my new design.

Fig. 2 is a top plan view of the lamp shade shown in Fig. 1.

I claim:

The ornamental design for a lamp shade, substantially as shown.

DAN DENENBERG.
